United States Patent Office.

JAMES WALSH, OF VALLEY TOWN, ILLINOIS.

Letters Patent No. 60,971, dated January 1, 1867.

IMPROVEMENT IN GRANARY.

The Schedule referred to in these Letters Patent and making part of the same.

TO ALL WHOM IT MAY CONCERN:

Be it known that I, JAMES WALSH, of Valley Town, in the county of Stark, and State of Illinois, have invented a new and improved Movable Granary and Measurer; and I do hereby declare the following to be a full, clear, and exact description of the nature, construction, and operation of the same, sufficient to enable one skilled in the art to which my invention appertains to make and use the same, reference being had to the accompanying drawing, which is made part of this specification, and in which my invention is represented by a perspective view.

The frame of this granary is so constructed as to be put up and sustained without pinning, so as to be readily moved; its internal measurement is such that every inch of height represents a certain capacity, so many bushels to every vertical inch of inside measurement. For instance, it is provided with partitions which divide its interior into separate chambers for the reception of definite proportions, for the convenience of dividing grain between claimants, as landlord and tenant, for instance, when threshing in the field, and is capable, by making one end in sections, of being used as a store-house; to which access is had from the end.

In the drawings, A A are longitudinal sills, which sustain the joists B B, the sills and joists being mutually gained into each other; C C are posts which have tenons at each end, the lower ends entering mortises in the joists, and the upper tenons occupying mortises in the ties D above. The square outside faces of the posts are recessed a short distance into the joists and ties, as shown at a, so as to give the full strength of the posts, and not depend upon the tenons alone. The outer ends of the ties D are framed into the beams E, which preserve them at their proper relative distance, as do the sills, the joists at the lower end. Inside of the frame thus constructed are the floor F and sides G; the former is laid upon the joists in the usual manner. The ends of the boards may be protected by the sheathing H, if desired; this is not a very material point. The siding G is placed, round by round inside the frame, the end boards being rabbeted into the side boards, as seen at b, or other suitable manner. I prefer the rabbeting to cleats, as I design to have some definite cubic capacity, and it is more easily estimated in a perfectly rectangular chamber, with but four sides, and no deductions for strips which project into the grain space. As I have said, it is my intention to have every inch of vertical height represent a number of bushels; and I will give the figures for one side, from which others may be calculated. A granary with upright sides and an inside clear measurement at bottom of 14 feet 11 inches by 8 feet, will hold eight (8) bushels in every inch of height; therefore, a granary of this area on the bottom, rectangular, and seven (7) feet deep, will hold 672 bushels of 2150.42 cubic inches each. This may be increased or diminished, according to the desired capacity, convenience of lumber, &c., varying with the purpose, location, &c. In many cases it is desired to divide grain in the field or barn, either temporarily or to leave it so stored; and in this case a partition may be introduced at any definite point, whose horizontal sectional area being known, will not materially complicate the calculation, or the sectional area of the division being equal to say two inches in width; the granary may be permanently provided with a division capable of being stationed at one-third of the length of the granary from the end, or one-half, &c., to suit the rental custom of the country, and two inches added to the length of the granary to make up for the deduction in the cubic clear capacity due to the partition. The partition L shown is one supported by posts, M, with side grooves, allowing the boards L to be slipped in or out so as to remove either of the series from floor to ceiling. This partition may be placed at one end instead of one of the other ends, as shown in the drawing, so as to answer for a doorway into the granary, which may be used as a store-house. I prefer to make the joists, sills, ties, posts, &c., respectively, of even size and shape, so that they may fill any situation suitable to their character. The amount of lumber required in building this granary is not greater than in one fastened by nails.

Having thus described my invention, what I claim as new, and desire to secure by Letters Patent, is—

The granary and measurer, constructed of removable parts, substantially as described and represented.

JAMES WALSH.
